B. BREARLEY.
SAFETY ATTACHMENT FOR DROP HAMMERS, &c.
APPLICATION FILED JAN. 27, 1912.

Patented June 25, 1912.

UNITED STATES PATENT OFFICE.

BEN BREARLEY, OF PROVIDENCE, RHODE ISLAND.

SAFETY ATTACHMENT FOR DROP-HAMMERS, &c.

1,030,381.

Specification of Letters Patent. Patented June 25, 1912.

Application filed January 27, 1912. Serial No. 673,856.

To all whom it may concern:

Be it known that I, BEN BREARLEY, a subject of the King of Great Britain, residing at Providence, in the county of Providence 5 and State of Rhode Island, have invented certain new and useful Improvements in Safety Attachments for Drop-Hammers, &c., of which the following is a specification.

10 This invention relates to a safety device adapted to be attached to drop-presses, or drop-hammers, as they are sometimes called, and it consists substantially in the novel construction, arrangement and combination 15 of parts, all as hereinafter set forth and claimed.

In drop-forging machines, or other analogous machines of this general type, the vertically movable hammer or stamping member 20 is liable to accidentally or prematurely drop; sometimes this happens before the dies are fully positioned or adjusted, resulting in injury to the workman, and in some cases causing injury to the dies or even to 25 the stock itself.

The object I have in view is to render drops or presses equipped with my invention practically incapable of causing accidental injury. In other words, I provide 30 the machine with a simple, semi-automatic safety-stop, as it may be termed, adapted, in case of abnormal action of the hammer, as for example, upon a breakage of the hammer's lifting-strap or belt while it is being 35 elevated, or even when the hammer is prematurely dropped, whereby the self-positioned interposed stop is adapted to arrest the hammer in its downward movement.

In the accompanying sheet of drawings, 40 Figure 1 represents, in front elevation, portions of a drop-hammer machine equipped with my improved safety-stop, the hammer being in normal working action; the stop at the same time being in the locked rearward position; Fig. 2 is a corresponding top plan view, in enlarged scale, the dotted lines indicate the extreme inward position the stop would automatically assume when it is released, and the hammer omitted or positioned above it; Fig. 3 is a front elevation, 45 in partial section, corresponding substantially with Figs. 1 and 2; Fig. 4 is a partial side elevation, viewed from the left of Fig. 3. The stop device, however, in this figure 50 is represented in the normally released position, corresponding with the dotted line po-

sition of the stop indicated in Fig. 2; Fig. 5 is a side elevation showing portions of the machine, viewed from the back; and Fig. 6 is a partial sectional view of the locking 60 and tripping device, its position corresponding with that shown in Fig. 2.

I may state that the safety attachment forming the subject of this application for patent is more particularly devised for use 65 in connection with metal swaging or forging machines in which the hammer is capable of being released from its elevated position by the operator—or even automatically—whereby the force or impact of the 70 hammer-blow upon striking the suitably positioned stock, in co-operation with the die or surface on which it is supported, causes the stock to be correspondingly transformed, 75 in a well-known manner.

Referring to the drawings, *a*, *b*, and *h* indicate, respectively, the bed or anvil, the uprights or guides, and the hammer members of a drop of usual construction. The adjacent faces of the anvil and hammer 80 may be adapted to receive die-holders *d*. The drawing also represents the vertically movable hammer member slidably mounted between the ways of the uprights and connected to a strap or flat belt *e*, through 85 which the hammer is adapted to be elevated. Means for lifting and releasing the hammer are not shown, since mechanism for this purpose are well-known and therefore not deemed essential to this specification. 90

The following is a more detailed description of the stop device and the manner of its operation:—The stop proper *A*, of suitable dimensions, is arranged to automatically swing onto the face of the die-holder *d* or other surface disposed below and in alinement with the hammer. The ends of the stop are counterbored or otherwise adapted to receive plugs *c* of rawhide or other substance possessing a degree of resiliency. Integral with the stop are arranged arms *f*—*f*, terminating in a vertical hub *i* mounted to vibrate on a headed post *e* tapped into a stud *k*, in turn secured to the anvil *a*—see Figs. 4 and 5. A set-screw *s* 95 engaging the lower or screw-threaded portion of the post, in connection with a spring *s*, interposed between the adjacent faces of said hub and stud, serve to maintain these parts in yielding vertical adjustment. The 100 upper end of the stop's hub *i* has a short lateral arm *f* arranged substantially oppo-

site the arms f , having a vertical pin m^3 fixed to its outer end, through which latter the stop is actuated.

A manually operable pull-rod m , having a reduced portion m^1 , extends transversely through one of the uprights b . To the rear end of the rod is secured a flanged ear m^2 jointed to the said vertical pin m^3 . A spring s , mounted on the part m^3 of the rod m and positioned between the upright and said ear, is adapted to automatically swing the stop to the extreme inward position when the latch-member c^1 , pivoted at c^2 , to the front of the upright, is temporarily disengaged from the portion m^1 of the rod n ; means consisting of a light spring s^2 acts to maintain the latch in yielding contact with the pull-rod, as clearly shown. It may be stated that the stop, when in the released position, is adapted to temporarily support the hammer thereon, substantially as indicated in Fig. 4.

Now, assuming that the several parts of the drop-forging machine or press and the safety-stop attachment have been properly adjusted and adapted for normal operation, whereby the hammer h , upon being released by the operator, will, in its descent to transform the stock positioned therebelow, engage the inner arm v^3 of the tiltable, spring-pressed latch c (previously actuated by the operator to swing and lock the stop A in the rearward position), and trip or release the latch from the endwise movable spring-pressed pull-rod, thereby at the same time permitting the spring s to move the stop inwardly to yieldingly bear against the back of the hammer before it (the hammer) arrives at a state of rest. Fig. 2 represents the normally locked stop before it has been thus released by the downwardly moving hammer. After the blow has been delivered the hammer itself is moved upward and supported at any desired height in a well-known way. During said upward movement the spring s causes the stop to swing inwardly and freely to its limit, thereby for the time being positioning it below and in alinement with the hammer, the stop then practically resting upon the face of the anvil or die-holder. Obviously, the member A automatically swings under the hammer just after the latter's base passes above the upper end of the stop. The dotted lines in Fig. 2, also Fig. 4, indicate the corresponding position. The attendant next, after performing the necessary operations incident to the normal action of the machine, pulls the rod m outward or toward the front, thereby swinging the stop rearwardly to its limit, the act also compressing the spring s and exposing the rod's reduced part m^1 , at which instant the arm c^1 of the spring-pressed latch drops onto it, thereby automatically locking the stop in position

until released—see Figs. 3 and 6. It may be added that said movement of the latch places the other arm c^3 in normal position again. The several elements now being in the normal positions, the operator next releases the supported elevated hammer, which, in falling to make the stamping-blow, engages the latch and automatically trips it, thereby, too, releasing the stop and permitting it to engage the back of the hammer, as before described. In case, however, the operator fails to move and lock the stop in the retracted position before he releases the upwardly supported hammer, the latter will, when released, fall on the stop's end instead of completing its normal stroke and blow. In the usual practice of setting or adjusting the dies in drop machines of this class, preparatory to normal working, the operator places a short wooden block on the anvil for the hammer to rest upon during the die-adjustment process. The block is removed and replaced during each of the tentative strikes of the hammer; the workman, in such die-setting tests, simply elevates the hammer a distance slightly exceeding the height of the block. If he fails to thus replace the block before the next succeeding blow, his hand or fingers are liable to be accidentally caught and severely injured. My improved safety-stop is well adapted to be thus employed in lieu of the wooden blocks. In such case the stop automatically swings under the hammer after each tentative strike or reduced blow, thereby avoiding the liability of accident to the operator, assuming, of course, that he moves and locks the stop A in the retracted position prior to releasing the hammer to make said reduced blow. The hammer, in falling, trips the stop so that it will automatically swing inwardly in position to support it after the next upward stroke of the hammer is made.

I claim as my invention and desire to secure by U. S. Letters Patent:—

1. In a safety-stop device for drop hammers or analogous machine, a movable stop member disposed with relation to the hammer, means for holding the stop in the normally retracted position, means, capable of being actuated by the hammer in its descent, for tripping or releasing the stop, and means provided for automatically moving the released stop inward between the anvil and hammer.

2. In a drop-hammer or analogous machine, the combination with the anvil and a guided, vertically movable hammer disposed above the top face of the anvil, of a safety-stop device having a laterally movable, spring-pressed member, constituting the stop proper, means for normally locking it in position with relation to the hammer, and tripping means adapted to be engaged by

the hammer for releasing the said stop, whereby it is adapted to move under the hammer automatically when the latter is raised a distance exceeding the height of 5 the stop.

3. In a drop-hammer machine, the combination with its anvil, uprights, and vertically guided hammer, of a safety-stop device fixed to said machine, said device including a vertically disposed stop proper, 10 A, means for locking the latter in the normal outward or retracted position, means capable of being tripped by the hammer for

releasing the stop from said retracted position, whereby it is adapted to automatically move inward under the hammer while the latter is being elevated, and manually controlled means for returning and locking the stop in the said normal retracted position.

In testimony whereof I have affixed my 20 signature in presence of two witnesses.

BEN BREARLEY.
